WALTER H. BROWN AND JOHN E. TRUCKSES, OF BOSTON, MASSACHUSETTS.

APPARATUS FOR MIXING AND DELIVERING AIR AND GAS.

SPECIFICATION forming part of Letters Patent No. 748,840, dated January 5, 1904.

Application filed February 28, 1903. Serial No. 145,499. (No model.)

To all whom it may concern:

Be it known that we, WALTER H. BROWN and JOHN E. TRUCKSES, both of Boston, in the county of Suffolk and State of Massachusetts, have invented certain new and useful Improvements in Apparatus for Mixing and Delivering Air and Gas, of which the following is a specification.

This invention relates to apparatus for mixing air and a combustible gas in predetermined proportions and supplying the same under pressure for use in heating, lighting, &c.

The invention has for its object to provide a simple, durable, effective, and automatically-operating apparatus of this character; and it consists in the improvements which we will now proceed to describe and claim.

Of the accompanying drawings, forming a part of this specification, Figure 1 represents a sectional elevation of an apparatus embodying our invention. Fig. 2 represents a section on line 2 2 of Fig. 1. Fig. 3 represents an enlarged elevation, partly in section, showing parts of the apparatus shown in Fig. 1. Fig. 4 represents a section on line 4 4 of Fig. 1 looking toward the left.

The same reference characters indicate the same parts in all the figures.

In the drawings, *a* represents a tank or reservoir open at its upper end and adapted to contain a body of water or other liquid to serve as a seal for the lower ends of two receivers *b* and *c*, each of said receivers being an inverted bell or tank closed at its upper end and open at its lower end and adapted to rise and fall in the liquid in the tank *a*. The receiver *c* is contained within the receiver *b* and is rigidly secured to the latter by a rod *d*, affixed to the tops or heads of the receivers *b* and *c* and causing said receivers to rise and fall in unison.

e represents an air-inlet which extends through the bottom of the tank *a*, its lower end being open to the atmosphere, while its upper end, which is provided with a downwardly-closing check-valve *e'*, is arranged to deliver air to the receiver *b* at a point above the liquid seal.

f represents a gas-pipe connected with a source of supply of combustible gas under

pressure, said pipe extending through the bottom of the tank *a* and upwardly into the receiver *c*, its upper end being provided with a downwardly-closing check-valve *f'*. The pipe *f* therefore delivers gas to the receiver *c*. 55

Means are provided for alternately raising the receivers *b* and *c* and for releasing said receivers and permitting them to descend by gravitation. When the receivers are raised, a partial vacuum is formed between their upper ends and the surface of the liquid in the tank *a*, so that air rushes through the air-inlet pipe *e*, raising the valve *e'* and filling the space in the air-receiver *b* above the liquid seal. At the same time gas enters the 65 upper portion of the gas-receiver *c* through the pipe *f*, the valve *f'* opening like the valve *e'*. When the receivers are released after having been raised and charged, respectively, with air and gas, the compression of the air 70 and gas in the upper portions caused by the descent of the receivers accomplishes two results—viz., first, the gas in the receiver *c* is forced from the latter into the air-receiver *b* through an outlet *c'* in the upper portion of 75 the gas-receiver *c*, said outlet having a downwardly-closing valve *c''*; secondly, the mixture of air and gas is forced from the air-receiver through a discharge-pipe *g*, which is continuously open within the air-receiver and 80 extends from a point above the liquid seal downwardly through the bottom of the tank *a* and then outwardly and upwardly into a gasometer *h* of ordinary construction. When the receivers are rising, the valve *c''* in the 85 outlet *c'* of the gas-receiver is closed by the vacuum in the gas-receiver below it, so that the gas does not escape from the gas-receiver until the downward movement of the receivers causes a pressure on the gas in the 90 gas-receiver.

The preferred means for raising and releasing the air and gas receivers are as follows:

i represents a vertical cylinder which is affixed to the bottom of the tank *a* and extends 95 upwardly within the gas-receiver *c* to a point above the liquid seal.

j represents a piston which is movable vertically in the cylinder *i* and fits the latter internally closely, said piston being affixed to 100

the rod d , which connects the receivers b and c , said rod being extended downwardly, as shown in Fig. 1.

k represents a conduit which communicates 5 with the lower end of the cylinder i and with the casing m of a three-way cock, in which is a movable plug member n . The cock-casing m has three branches 2, 3, and 4. The branch 10 2 with a supply-pipe o , communicating with a source of supply of water or other fluid under pressure, and the branch 4 is connected with a waste-pipe p . The plug n is tubular and is provided with a peripheral groove n' , 15 Fig. 3, which when the plug is at one extreme of its movement coincides with the branches 2 and 3, so that water from the supply-pipe o can pass through the cock-casing to the conduit k and from the latter into the cylinder i , 20 the branch 4, leading to the waste-pipe p , being at this time shut off from the branches 2 and 3 by the lower end of the plug n . The fluid thus admitted to the cylinder i acts on the piston j to raise the latter and, through 25 the rod d , the air and gas receivers b and c .

r represents a weighted lever pivoted at r' to a fixed support and having a segmental slot r^2 in one of its arms, said slot receiving a pin n^2 , connected with the stem of the plug 30 n . The said lever has another arm, to which is pivotally connected the lower end of a vertical rod s , which is provided at its lower portion with a shoulder s' and at its upper portion with a shoulder s^2 .

35 t represents a tubular member affixed to the top of the air-receiver b and having at its lower end an inwardly-projecting flange t' , which is adapted to engage either the shoulder s' or the shoulder s^2 , the upward movement of the receivers causing the flange t' to engage the shoulder s^2 and lift the rod s , thereby swinging the lever r in the direction required to depress the plug n , while the downward movement of the receivers causes 45 the flange t' to engage the shoulder s' and depress the rod s and cause a movement of the lever r in the direction required to raise the plug n . When the plug is depressed, its peripheral recess n' is moved out of alinement 50 with the branches 2 and 3 of the cock-casing, and a port n^3 in its side is brought into alinement with the branch 3. The inlet branch 2 is now closed, and the branch 3 is connected, through the port n^3 and the interior of the 55 plug, with the outlet branch 4 and the waste-pipe p , so that the fluid which has been forced into the cylinder i and has raised the piston j therein is released and permitted to drain off through the conduit k and waste-pipe p , 60 the air and gas receivers being thus permitted to descend.

The segmental slot r^2 is concentric with the pivot r' , on which the lever r swings, so that the lever is loosely engaged with the cock- 65 plug and can swing a distance equal to the length of the slot before moving the plug.

The loose connection afforded by the slot r^2 therefore enables the lever to swing past its vertical position and begin to swing downwardly by gravitation before moving the plug, 70 so that the plug is moved quickly in each direction by the momentum of the falling weight.

From the foregoing it will be seen that each upward movement of the air and gas receivers 75 causes the upper portions of said receivers to be charged, respectively, with air and gas and that at the end of the upward movement the cock-plug n is moved to release the water from the cylinder i and permit the descent of 80 the receivers, the gas in the gas-receiver being thereupon caused to mingle with the air in the air-receiver and the mixture of air and gas forced through the discharge-pipe g into the gasometer h . At the end of the downward 85 movement of the receivers the cock-plug n is raised to close the outlet 4 to the waste-pipe and connect the supply-pipe o with the conduit k , leading to the cylinder. The impelling fluid is thus admitted to the cylinder and caused 90 to raise the air and gas receivers, this operation being continued indefinitely. It will be seen that the proportions of air and gas admitted are according to the capacity of the receivers b and c above the water seal. The 95 volume of gas required being usually less than that of the air, the gas-receiver is preferably made smaller, both in height and diameter, than the air-receiver, as shown in Fig. 1, this difference in size enabling the 100 gas-receiver to be conveniently placed within the air-receiver. The volume of the mixture of air and gas delivered may be approximately determined by means of a meter or indicator u , affixed to a frame or support above 105 the receivers b and c and having a member formed as a projecting lever u' , arranged to be moved by a stud or projection u^2 on the top of the air-receiver when the latter rises. Each movement thus imparted to the lever 110 u' is caused to turn an actuating-train in a manner which will be well understood.

Means are provided whereby the rise of the floating or bell member h' of the gasometer may be caused to shut off the supply of impelling fluid from the pipe o to stop the delivery of the air and gas mixture to the gasometer when the latter is full and also whereby the descent of the bell h' may be caused to admit the supply of fluid under pressure 115 to the pipe o , thus starting the operation of the air and gas mixing and delivering apparatus. To these ends the bell h' is provided with an ear or projection h^2 , which is movable between projections v and v' on a vertical rod v^2 , said rod being connected by suitable means, such as a shoulder v^3 and an arm v^4 , with a shut-off valve or cock, the casing v^5 of which is shown in Fig. 4, said casing forming a part of the supply pipe or conduit 120 o . When the bell h' reaches the limit of its upward movement, the projection h^2 strikes 125

the shoulder v , raising the rod v^2 and closing the valve at v^5 . When the bell h' descends in consequence of the consumption of the stored gas, the projection h^3 eventually strikes the projection v' , thus depressing the rod v^2 and causing it to open the valve at v^5 . The end of the discharge-pipe g within the gasometer is provided with a downward-closing check-valve g' , which is closed when the outward flow from the receivers ceases and prevents the pressure within the gasometer from forcing the mixture of gas and air backwardly through the pipe g , the said mixture being forced outwardly to the burners through a pipe w .

We claim—

1. An air and gas mixing and delivering apparatus comprising two connected inverted receivers, a liquid seal closing the lower ends of said receivers, means for alternately raising and releasing said receivers, the said receivers having inlets through which air and gas enter when the receivers are rising, the gas-receiver having also an outlet through which the gas passes to the air-receiver, and a discharge-pipe to conduct the mixture of air and gas from the air-receiver when the receivers are descending.
2. An air and gas mixing and delivering apparatus comprising two connected inverted receivers, a liquid seal closing the lower ends of said receivers, means for alternately raising and releasing said receivers, the said receivers having inlets through which air and gas enter when the receivers are rising, the gas-receiver having also an outlet through which the gas passes to the air-receiver, a discharge-pipe to conduct the mixture of air and gas from the air-receiver when the receivers are descending, and means for preventing the escape of said mixture excepting through the discharge-pipe.
3. An air and gas mixing and delivering apparatus comprising two connected inverted receivers, a liquid seal closing the lower ends of said receivers, means for alternately raising and releasing said receivers, the said receivers having inlets through which air and gas enter when the receivers are rising, the gas-receiver having also an outlet through which the gas passes to the air-receiver, a discharge-pipe to conduct the mixture of air and gas from the air-receiver when the receivers are descending, and downwardly closing check-valves in the air and gas inlets and in the gas-outlet, whereby the escape of said mixture excepting through the discharge-pipe is prevented.
4. An air and gas mixing and delivering apparatus comprising two connected inverted receivers, a liquid seal closing the lower ends of said receivers, a fixed vertical cylinder extending through said seal, a piston movable in the cylinder and connected with the receivers, means operated by the descent of the receivers to admit an impelling fluid under pressure to the cylinder below the piston to raise the receivers, and by the rise of the receivers to shut off the impelling fluid and permit the drainage of the cylinder and the descent of the receivers by gravitation, said receivers having inlets through which air and gas enter when the receivers are rising, the gas-receiver having also an outlet to the air-receiver, a discharge-pipe to conduct the mixture of air and gas from the air-receiver when the receivers are descending, a gasometer arranged to receive the mixture of gas and air from the air-receiver, and means controlled by the floating bell or chamber of the gasometer for alternately turning on and shutting off the impelling fluid.
5. An air and gas mixing and delivering apparatus comprising two connected inverted receivers, a liquid seal closing the lower ends of said receivers, means for alternately raising and releasing said receivers, the said re-

receivers to admit an impelling fluid under pressure to the cylinder below the piston to raise the receivers and by the rise of the receivers to shut off the impelling fluid and permit the drainage of the cylinder and the descent of the receivers by gravitation, said receivers having inlets through which air and gas enter when the receivers are rising, the gas-receiver having also an outlet to the air-receiver, and a discharge-pipe to conduct the mixture of air and gas from the air-receiver when the receivers are descending.

5. An air and gas mixing and delivering apparatus comprising two connected inverted receivers, a liquid seal closing the lower ends of said receivers, a fixed vertical cylinder extending through said seal, a piston movable in the cylinder and connected with the receivers, a conduit entering the lower portion of the cylinder, a three-way-cock casing communicating with said conduit and having an inlet connected with a source of supply of fluid under pressure and a drainage-outlet, a cock-plug movable in said casing and having means for connecting the said conduit alternately with the inlet and with the drainage-outlet, an oscillatory weighted lever pivoted to a fixed support and having an arm containing a segmental slot receiving a stud in the stem of said plug, a vertical rod connected with another arm of said lever, said rod having two shoulders, and a member moving with the receivers and adapted to engage one of said shoulders when the receivers are rising, and the other shoulder when the receivers are descending.

6. An air and gas mixing and delivering apparatus comprising two connected inverted receivers, a liquid seal closing the lower ends of said receivers, a fixed vertical cylinder extending through said seal, a piston movable in the cylinder and connected with the receivers, means operated by the descent of the receivers to admit an impelling fluid under pressure to the cylinder below the piston to raise the receivers, and by the rise of the receivers to shut off the impelling fluid and permit the drainage of the cylinder and the descent of the receivers by gravitation, said receivers having inlets through which air and gas enter when the receivers are rising, the gas-receiver having also an outlet to the air-receiver, a discharge-pipe to conduct the mixture of air and gas from the air-receiver when the receivers are descending, a gasometer arranged to receive the mixture of gas and air from the air-receiver, and means controlled by the floating bell or chamber of the gasometer for alternately turning on and shutting off the impelling fluid.

7. An air and gas mixing and delivering apparatus comprising two connected inverted receivers, a liquid seal closing the lower ends of said receivers, means for alternately raising and releasing said receivers, the said re-

ceivers having inlets through which air and gas enter when the receivers are rising, the gas-receiver having also an outlet through which the gas passes to the air-receiver, a discharge-
5 pipe to conduct the mixture of air and gas from the air-receiver when the receivers are descending, and an indicator or meter operated by the movements of the receivers.

In testimony whereof we have affixed our signatures in presence of two witnesses.
